UNITED STATES PATENT OFFICE.

LOUIS McMURRAY, OF BALTIMORE, MARYLAND.

PROPELLED APPARATUS FOR VESSELS.

SPECIFICATION forming part of Letters Patent No. 391,481, dated October 23, 1888.

Application filed May 3, 1887. Serial No. 236,919. (No model.)

To all whom it may concern:

Be it known that I, LOUIS McMURRAY, of the city of Baltimore and State of Maryland, have invented a new and useful Improvement 5 in Apparatus for Propelling Steamboats, of which the following is a full description.

Figure 1 of the drawings is a longitudinal section of a boat, showing the boiler and propelling apparatus; Fig. 2, a front elevation 10 showing sprocket-wheels and endless chain, the open passage-way for the paddles beneath the boat, and grating to intercept débris or other matter; Fig. 3, a cross-section of the boat, showing sprocket-wheel which operates the endless 15 chain which carries the paddles, the open passage-way beneath the boat, and paddle therein; Fig. 4, a perspective view of paddle, part of endless chain to which paddle is attached, block of wood inserted between the wings of 20 the paddle, and guiding-bars. Fig. 5 is a sectional diagram illustrating two open passage-ways beneath the boat with double sets of paddles.

Let A represent the hull of a boat cut out 25 below at B to form a passage-way running from stem to stern. This passage-way may be increased in depth by securing thereto the projections b². Upon these projections are secured the guide-pieces b³, the object of which 30 is to guide and sustain projections from the paddle-chain to steady the paddles as they move through the passage-way.

A driving-engine is erected upon any suitable part of the boat, which is connected by 35 appropriate mechanism with the propelling devices. Upon suitable supports and bearings is placed the shaft C, which runs across the boat and is provided with the sprocket-wheels c, located at suitable places on the shaft. A 40 cog-wheel upon the driving-shaft of the engine meshes with one on the shaft C and imparts revolution to that shaft.

Erected upon the boat fore and aft of the engine is the frame D, and upon this frame-work 45 are placed the brackets or supports d'. Secured to these supports are the bearings which sustain the shafts E E'. These shafts are provided with sprocket-wheels e², arranged in line with the sprocket-wheels on the shaft C, so as 50 to receive the chain which passes around these wheels. These chains are marked in the draw-

ings c² c³. Arranged somewhere about midway of the shafts E are other sprocket-wheels, e⁴, designed to carry the bucket or paddle chain F, and upon the lower part of the frame-work B 55 other shafts are erected in suitable bearings, which carry similar sprocket-wheels, e⁵. In cases where two sets of paddles are used, as shown in Fig. 5, those wheels are not placed centrally upon the shafts, but are duplicated 60 and arranged in line to suit the open passage-ways beneath the boat. It will be seen by this arrangement that an open box is formed in the shape of a parallelogram, leaving ample space for deck-room, the under side of which is the 65 open passage-way beneath the boat. By this arrangement it will be seen that when the engine is started the paddle passing through the passage-way will propel the boat in either direction, and as the paddles beneath the water 70 are guarded on both sides there is little or no agitation of the water sidewise, and in cases where boats are propelled in narrow channels the washing of the banks from this cause would be very little. Such construction of boat also 75 displaces less water than those which are solid to the keel. This passage-way may be protected, if desired, from obstruction of ice or rubbish by the grating G, placed in front or at both ends.

The buckets or paddles H are attached to the chain by rivets, or in any suitable manner, as shown in Fig. 4, and are provided with the cross-bars h h, secured thereto in a suitable manner and projecting beyond the sides of the 85 buckets, as shown in Fig. 4. The ends of these bars enter the guideways b³, Figs. 3 and 5, and steady the buckets in their course under the boat. The buckets may be strengthened by the insertion between the sides of a solid block of 90 wood or other material, as shown at h', Fig. 4, and these blocks may be secured therein by the bolts h².

Having described my invention, what I claim, and desire to secure by Letters Patent, is—

1. In a steamboat provided with a propelling device consisting of an endless carrier to which is secured a series of buckets, the buckets formed of a back piece for securing it to the carrier, and two side pieces or wings projecting therefrom at right angles, and having inserted between said wings a block of wood

or other suitable material, substantially as set forth.

2. A steamboat having its hull cut out below to form a longitudinal passage-way beneath the boat, in combination with an endless carrier provided with buckets formed of a back piece for securing it to the carrier, and two side pieces or wings projecting therefrom at

right angles, and having inserted between said wings a block of wood or other suitable material, substantially as set forth.

LOUIS McMURRAY.
